CLAIM

The ornamental design for a silicone tray as shown and described.

DESCRIPTION

FIG. 1 is a front, right and top perspective view of a silicone tray showing my new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is a front, right and top perspective view thereof, showing a cover on top of the silicone tray.

The broken lines illustrate environment that forms no part of the claimed design.

1 Claim, 9 Drawing Sheets
